UNITED STATES PATENT OFFICE.

JOHN W. SPARKS, OF SABINA, OHIO.

AUTOMATIC RAILWAY-SWITCH.

No. 921,175.

Specification of Letters Patent.

Patented May 11, 1909.

Application filed July 30, 1908. Serial No. 446,178.

To all whom it may concern:

Be it known that I, JOHN W. SPARKS, a citizen of the United States, residing at Sabina, in the county of Clinton and State of Ohio, have invented certain new and useful Improvements in Automatic Railway-Switches; and I do hereby declare the following to be a full, clear, and exact description of the invention, such as will enable others skilled in the art to which it appertains to make and use the same.

This invention relates to automatic train-operated switches, and particularly that type of switches which can be operated either manually by means of any ordinary switch-lever or automatically by an instrumentality carried by the passing train, the switch-bar being divided or separable between the track and switch-stand so as to permit independent displacement of that member or portion of the switch-bar to which the movable switch-points are connected. An example of such switches is exhibited in U. S. Patent to Sparks and Allen, No. 883,358, dated March 31, 1908, upon which the present invention may be considered an improvement.

The object of the invention is to perfect and more especially to simplify the construction of automatic switches of the character stated, providing a switch-mechanism of very few parts, one that can be readily installed or applied to existing switch-stands, and which will be reliable and efficient in operation. For attaining this object, and with a view principally to simplicity, the automatic closing of the switch, when the train is passing in a direction toward or against the switch-points, is effectuated by engagement of the instrumentality carried by the locomotive with a movable bar, rail or member arranged obliquely to the track-rails and connected to the displaceable member of the switch-bar, and, when the train is passing in the opposite direction, by the same means or by lateral pressure of the wheel-flanges against the switch-points, or both; and in conjunction with such displacement of the main portion of the switch-bar, contracting or extending the length of the bar as a whole according to whether the switch-stand is located on the switch-side or other side of the track, a spring-impelled detent is employed to lock the said displaceable member

of the switch-bar in the position to which it is forced when the switch is closed automatically.

The invention will be described with reference to the accompanying drawings, which form a part of this specification, and will be more particularly pointed out or defined in the appended claims.

In said drawings: Figure 1 is a plan view of a switch embodying this invention, showing the switch open and indicating closed position by dotted lines. The switch-stand appears on the opposite side of the track from the siding, that is opposite from the switch side, which is considered the preferred arrangement. The closing-bar 6 shown between the track-rails is also capable of location at the side of the track, which position thereof is indicated by dash and dot lines. Fig. 2 is a side elevation of a part of the separable switch-bar together with the aforesaid locking detent. This view shows the switch-bar in normal position, adapted to be shifted manually by the switch-lever for opening and closing the switch; that is before the main member of the switch-bar has been displaced automatically. Fig. 3 is a longitudinal vertical section of Fig. 2 taken after automatic closing of the switch, the detent being in service. Fig. 4 is a plan view of another form of divided switch-bar and locking detent, this view showing the normal position of said switch-bar or before displacement by automatic closing. Fig. 5 is a longitudinal vertical section of Fig. 4 taken after displacement by automatic closing, showing the detent in service. Fig. 6 is a longitudinal section of another form of divided switch-bar and detent suitable for a construction when the switch-stand is located on the switch-side of the track, or the same side as the siding. This section is taken before displacement; and the position of the parts after displacement is shown in dotted lines. Fig. 7 is a modification of Fig. 6.

1 denotes the main track rails, 2 the side track rails, and 3 the movable switch-points connected to the shiftable switch-bar 4, which latter is connected to and adapted to be operated by any suitable switch-lever 5 or other switch-throwing device for closing and opening the switch.

In view of the division in the switch-bar,

which division occurs between the track and switch-lever, for the sake of clearness the symbol 4 is applied in the drawings to the main member or portion of the switch-bar 5 to which the switch-points 3 are connected, while the symbol 4^a is applied to the shorter separate length of the switch-bar which is connected to the switch-lever 5.

In accordance with the principle disclosed 10 in said Patent No. 883,358, the two members of the switch-bar are joined in such manner as to operate normally as a rigid or unitary switch-bar, under throw of the lever 5 for manual control of the switch; while yet the 15 main-member 4 or switch-bar proper is capable of an independent endwise displacement to allow automatic closing of the switch independently of or without affecting the switch-lever. But instead of the operating 20 mechanism disclosed in said patent, which included positively-driven wedges adapted to enter between and part two bearing-surfaces for displacing the bar 4, there is provided either between the track-rails or at the 25 side of the track an obliquely-disposed long bar 6 connected to the switch-bar and adapted to be engaged by an instrumentality carried by the locomotive-pilot, so that if the train approaches an open switch the switch- 30 bar or main member thereof will be displaced in a direction to close the switch; and, as previously mentioned, in conjunction with such operating means a spring-im- 35 pelled detent is employed for securing the switch-bar in its displaced position and thereby locking the closed switch. The said inclined bar 6 is secured to the track at 7, in advance of the switch-points, and its fastenings are such as to allow a lateral 40 play or displacement as indicated by dotted lines in Fig. 1.

One of various suitable constructions for the separable switch-bar and locking detent is illustrated in Figs. 2 and 3; the same being 45 adapted for a switch-stand located on the opposite side of the track from the siding, hence requiring extension of the switch-bar or displacement of the member 4 away from the switch-lever for automatic closing of the 50 switch. In this construction, the members 4 and 4^a of the switch-bar have overlapping end portions slidable one upon the other in guides or loops 8 and formed as half-boxes 9 to contain a coiled expansion spring 10. Said spring 10, under compression between 55 the opposite ends of the two half-boxes 9, holds the switch-bar to its shorter length and tends to resist displacement of member 4; the movement of the two members under force of 60 the spring being limited by a lug or projection 11 on member 4 adapted to abut against the box-like end of the member 4^a. It will be obvious that by this connection the members 4 and 4^a will be normally held as in Fig.

2 and operate as a unitary or rigid switch-bar 65 under manipulation of the switch-lever 5. A spring-detent 12 secured on or to member 4^a bears upon the lug or projection 11 on member 4. When the switch is automatically closed, the displaceable member 4 is forced 70 against resistance of the spring 10 until the lug 11 is carried from under the detent 12 which immediately snaps behind said lug and locks the mechanism, as represented in Fig. 3. The loops 8, one of which is fastened on 75 member 4 and the other on member 4^a, each consist of two stirrups or half-parts bolted together, as shown in Fig. 2, so as to permit taking apart for insertion and removal of the spring 10.

Another construction somewhat similar to the divided switch-bar shown in the aforesaid patent, is represented in Figs. 4 and 5. Here the adjacent ends of the two members 4 and 4^a of the switch-bar are formed with upstanding abutting lugs or heads 13, and a transverse rod 14 is passed loosely through apertures in said lugs and stout coiled springs 15 are arranged on said rod at opposite sides of the lugs, said springs 15 being housed or contained in boxings 16 extending from said lugs 13; so that the force of said springs normally holds the lugs or heads 13 together. In this case, the locking detent consists of a spring-impelled lug 17 which, when the 95 switch is automatically closed and the lugs 13 parted by displacement of member 4, enters between the separated lugs and locks the mechanism, as shown in Fig. 5. The spring for the lug 17 is indicated at 18. A 100 stud 19 on said lug affords means for retracting it to allow resetting the mechanism.

Fig. 6 shows a construction for a switch-stand located on the switch side of the track, where automatic closing of the switch necessitates displacement of member 4 toward the switch-lever, so as to shorten instead of extend the switch-bar. In this case, the members 4 and 4^a have box-like overlapping end portions, after the manner of Figs. 2 and 3, and an inclosed expansion spring 20 acting between lugs 21 and 22 on the two members tends to hold the divided or separable switch-bar extended, motion being limited by the other lugs or heads 21 and 22. When the 105 switch is automatically closed, causing shortening of the switch-bar and consequent compression of spring 20, a spring-hook 23 on one member of the switch-bar snaps behind a catch or projection 24 on the other member; said hook 23 thus constituting the locking detent for this form of embodiment.

Fig. 7 shows a variation of Fig. 6 in which two coiled springs are used, instead of one, by a different arrangement of the lugs 21 110 and 22.

From the foregoing, it will be obvious that the invention is not to be confined to any

specific form of mechanism for connecting the members of the separable switch-bar, nor any particular form of locking detent; both of which are susceptible of embodiment 5 in various forms.

The operation is as follows: Assuming that the switch has inadvertently been left open, and a train is approaching the switch in a direction toward or against the switch-points (from left to right in Fig. 1), a suitable switch-operating instrumentality carried by the pilot of the locomotive will engage the long inclined bar 6, sliding or rolling along the side thereof, and by lateral pressure 10 against said bar displace the member 4 of the separable switch-bar, thereby closing the switch before the engine-wheels reach the switch-points; the mechanism being at the same time automatically locked by the 15 spring-impelled detent as already described. If the train is moving in the opposite direction, the lateral pressure of the wheel-flanges against the movable switch-points will accomplish the same result; or as an additional 20 precaution the same instrumentality on the engine may engage the point 25 of bar 6, which as shown extends across the switch-bar and has a curved end for that purpose. After a train has passed over an open switch 25 and effected closing and locking of the same, the switch remains closed until the switch-man releases the locking detent, whereupon the mechanism under force of the spring or springs in the switch-bar becomes reset in its 30 normal relation to the manual switch-lever. The invention will thus effectually prevent accidents by a train running into an open switch when it should continue on the main line.

40 As will be apparent, the invention is exceedingly simple, comprises only a few parts, and hence is inexpensive to install and maintain; and it can readily be applied to any ordinary switch-stand merely by providing 45 the closing bar 6 and substituting the separable switch-bar with spring detent for the ordinary switch-bar.

It is to be understood that the foregoing apparatus is to be used in connection with 50 any suitable instrumentality carried by the engine pilot and adapted to throw the bar 6; such instrumentality being adapted to be thrown or moved vertically from the bottom of the pilot or moved to operative or inoperative position by suitable connections leading to the locomotive-cab, as well understood in the art to which this invention pertains. It 55 is intended of course that such instrumentality shall always remain in operative position except when it is desired to allow switching.

By reference to Figs. 2 and 3 it will be seen that the bar 6 projects above the rails and switch-points; and therefore the instrumen-

tality X, carried by the locomotive-pilot, and 65 which operates the bar 6, will pass over the rails and switch points without contacting therewith.

Having thus described my invention, what I claim as new and desire to secure by Letters Patent of the United States is:

1. In a railway switch, the combination with the movable switch-points, of a switch-bar connected thereto, means for manually reciprocating the switch-bar, the switch-bar 75 having a portion thereof adapted for displacement independently of the other portion, and the switch-bar being operable manually as a unitary bar, train operable means for moving said displaceable portion 80 of the switch-bar in a direction for closing the switch, and an automatic detent adapted to lock the switch when closed by said train-operable means.

2. In a railway switch, the combination 85 with the movable switch-points, of a switch-bar connected thereto and having a portion thereof adapted for independent displacement, resilient means holding the displaceable portion of the bar in normal relation to 90 the remainder thereof, means for manually reciprocating the switch-bar, and a movable bar engaging the displaceable portion of the switch-bar and operable to move said portion against its resilient means in closing the 95 switch, said movable bar being adapted to be operated by an instrumentality carried by the train to close the switch.

3. In a railway switch, the combination 100 with the movable switch-points, of a switch-bar connected thereto, a manual switch-throwing device operatively-connected to said switch-bar, the latter being independently displaceable endwise, and a movable 105 bar connected to said switch-bar and arranged obliquely to the track-rails and adapted to be engaged by a suitable instrumentality carried by the train for displacing said switch-bar in a direction to close the switch, and an automatic detent for locking 110 said switch-bar when the switch is closed by said oblique bar.

4. In a railway switch, the combination 115 with the movable switch-points, of a switch-bar connected thereto, a switch-throwing device operatively-connected to said switch-bar, said switch-bar being divided to be separable between the track and switch-throwing device but adapted to operate normally as a unitary bar, a member or bar on the track 120 adapted to be moved laterally by train-provided means and connected to that member of the switch-bar to which the switch-points are connected, for automatically closing the switch, and a spring-impelled detent adapted 125 to lock said member of the switch-bar when displaced by such automatic switch-closing.

5. In an automatic train-operated switch,

5 a divided switch-bar comprising two members, a spring or springs maintaining said members in normal relation to operate manually as a unitary bar while allowing displacement by a train of that member to which the switch-points are connected, and a spring-impelled detent adapted to engage and lock the latter member in displaced position.

6. In an automatic train-operated switch, 10 a divided switch-bar comprising two members, a spring or springs maintaining said members in normal relation while allowing displacement of that member to which the switch-points are connected, a spring detent 15 on one member, and a catch on the other member adapted to be engaged by said detent for locking the displaceable member in its displaced position.

7. In an automatic train-operated switch, 20 a divided switch-bar comprising two members having overlapping portions slidable one upon the other and formed as half-boxings, a spring or springs arranged between said overlapping portions and abutting with its 25 opposite ends the opposed half-boxings and maintaining the two members in normal relation while allowing displacement of that member to which the switch-points are connected, a spring detent carried by one member, and a catch on the other member adapted 30 to be engaged thereby for locking the displaced member.

8. In a railway switch, the combination 35 with the movable switch-points, of a switch-bar connected thereto, said switch-bar hav-

ing a portion adapted for independent displacement, and a movable bar operably connected to the switch-bar and adapted to be actuated by a train moving in either direction to displace said displaceable portion of the 40 switch-bar to throw the switch.

9. In a railway switch, the combination 45 with the movable switch-points, of a switch-bar connected thereto and formed by a plurality of members, projections carried by the members, a spring interposed between opposed projections carried by the members and adapted to hold them in normal relation, and means operable to throw the switch by displacing one member of the switch-bar 50 against the force of the spring, detent means for holding the members in displaced position, the spring returning the members to their normal position upon retraction of the 55 detent means.

10. In a railway switch, the combination 60 with the movable switch-points, of a switch-bar connected thereto, and a movable bar operably connected to the switch-bar and adapted to be actuated by a train to throw the switch, said movable bar being operable by a train when moving from either right to left.

In testimony whereof I affix my signature, in presence of two witnesses.

JOHN W. SPARKS.
